CLAIM

The ornamental design for a lacebite prevention cushion, as shown and described.

DESCRIPTION

FIG. 1 is a front perspective view of a first embodiment of the lacebite prevention cushion;

FIG. 2 is a front plan view thereof;

FIG. 3 is a rear view thereof;

FIG. 4 is a front environmental view showing a laced skate boot;

FIG. 5 is a top environmental view with the skate boot partially open to show the lacebite prevention cushion; and, FIG. 6 is a second top environmental view with the skate boot fully open to show the lacebite prevention cushion. The broken line showing of a laced skate boot is included for the purpose of illustrating environmental structure only and forms no part of the claimed design.
